UNITED STATES PATENT OFFICE.

FREDERICK D. PITTS AND ARTHUR OSTERLOO, OF KANSAS CITY, MISSOURI, ASSIGNEES
TO THE ANDERSON-PITTS CORPORATION, OF KANSAS CITY, MISSOURI, A CORPORA-
TION OF MISSOURI.

GUARD FOR ELECTRIC HEATERS.

Application filed December 7, 1925. Serial No. 73,698.

Our invention relates to a guard for electric heaters or the like, and more particularly to a device of that character for protecting the heater element from damage by contact with exterior objects, and persons or articles from injury or damage by contact with the heater element, the principal object of the invention being to provide a guard of that kind which is simple and economical in construction and assembly and in which the parts are more securely connected than are those of the guards in ordinary use.

In accomplishing this object we have provided improved details of structure, the preferred forms of which are illustrated in the accompanying drawings wherein:—

Fig. 1 is a perspective view of an electric heater equipped with a guard embodying our improvements.

Fig. 2 is an enlarged, vertical section of the guard, illustrating its mounting on the heater body, parts of the body being in section.

Fig. 3 is an enlarged detail perspective view of a portion of one of the ribs of the guard.

Fig. 4 is a similar view, showing frame elements in place on the rib.

Fig. 5 is a similar view showing the anchorage of the frame member.

Fig. 6 is an enlarged side elevation of a part of one of the ribs, illustrating the mounting of the frame members therein.

Referring more in detail to the drawings, 35 1 designates the base and 2 the body member of an electric heater of any suitable construction, the body member having ears 3 by which it is pivotally mounted on the base by a bolt 4 and wing nut, whereby the body may be locked at various angles to adjust the direction of flow of heated air within a room or space served by the heater. The body 2 is preferably of sheet metal construction, spun or otherwise shaped to concavo-convex formation and having a peripheral, inturned flange 5 spaced from the body proper to provide an inwardly opening seat 6, the face of the body member being lined with a reflecting surface 7 whereby heat rays emanating from a heating element, presently described, are deflected through the open front of the heater.

Located centrally of the body member and in spaced relation to the deflector 7 is a heat-

ing element, preferably consisting of a core 55 9 upon which is wound a resistance wire 10, the terminals 11 and 12 of which extend through the body member for connection with the line wires of a lighting system.

Our improved guard construction adapted 60 for use with the heater embodying the elements above described, comprises curved ribs 13 of heavy sheet or light bar metal, each having a notch 14 in its outer edge near one end, to seat the end of the rib within the body seat 6 and having spaced notches 15 in its inner edge for seating the frame members 16.

The frame members 16 are preferably convolutions of a single piece of wire coiled to 70 form the concavo-convex guard frame, the convolutions being spaced to seat the wire within the notches 15 of the respective rib members. While any suitable number of ribs may be employed, we prefer to use four, 75 spaced 90 degrees apart and of such curvature and inclination that the inner ends of the ribs are spaced slightly at the center of the guard.

With this arrangement of the parts, the 80 frame member is spiralled in convolutions of gradually increasing diameter, and the frame dished to form a concavo-convex guard for the heater element.

In assembling the guard, the ribs are pref- 85 erably seated in a die (not shown) in order to maintain their proper spacing, and the wire spiralled and seated in the notches in the respective ribs, one of the ribs having an elongated, undercut slot 17 adapted to seat 90 two strands of the wire so that when the coiling is begun, the free end of the wire and the first convolution are seated in the slot 17 and one locks the other, the spring 95 tension of the wire forcing the same longitudinally in the slot to frictionally lock the wire to the rib. To insure the locking action we preferably undercut the slot at both ends so that after the wire has been projected through the throat 18 into the slot, each 100 strand will force the other away from the throat to prevent accidental escape of the wire from the slot.

When the wire has been anchored as de- 105 scribed, the convolutions are successively located in the rib notches and the material at the edge of the ribs peaned over with a chisel or other tool to lock the wire in the notches

15. A bifurcated chisel blade may be employed to strike the lips 19 and 20 in the ribs simultaneously and effect the peaning with one operation of the tool.
- 5 16. The guard, assembled in this manner, is applied bodily to the body 2 of the heater, the ribs being sprung back to enable the notched portions 14 to seat within the body slot 2, resiliency of the frame wire tending 10 to spread the guard to maintain the ribs in their seats when all are in place.

It is apparent that with this construction, use of frame rings of different diameters is avoided, that the guard elements may be 15 easily and quickly assembled, and securely and permanently associated, and that the guard may be securely but removably applied to the body of the heater.

What we claim and desire to secure by Letters-Patent is:—

1. A guard of the character described, comprising spaced ribs having edge notches and frame members seated within the notches, the edges of the ribs being peaned 25 over the frame members to lock the parts together.
2. A guard of the character described, comprising ribs having spaced edge notches, a spiralled wire having its convolutions seated in the rib notches, the edges of the ribs adjacent the notches being peaned over the wire to hold the wire to the ribs.
3. A guard of the character described, comprising spaced, similarly curved ribs 35 having spaced notches in their inner edges and a spiralled wire having its convolutions seated in corresponding rib notches, the edges of the ribs being peaned over the convolutes of the wire.
40. 4. A guard of the character described, comprising curved ribs having similarly spaced notches in their inner edges, an end notch of one of the ribs being enlarged to form an undercut slot, a spiralled wire having 45 the inner end of its first convolution

seated in said undercut slot, and the successive convolutions of the wire seated in corresponding notches of the respective ribs, the edges of the ribs being peaned over the wire to lock the parts together.

5. A guard of the character described comprising spaced, curved ribs having correspondingly spaced notches in their inner edges, and a frame wire spiralled and seated in the rib notches, the edges of the ribs being peaned over the wire to lock the parts together, the ribs having notches in their outer edges adjacent their outer ends for seating in the seat in a body member to hold the guard to the body member.

6. A guard of the character described comprising a concavo-convex body consisting of spaced ribs having spaced, transverse notches in their inner edges and a wire spiralled and seated in said notches.

7. A guard of the character described comprising a concavo-convex body consisting of spaced ribs having spaced, transverse notches in their inner edges and a wire spiralled and seated in said notches, the ribs having transverse notches in their outer edges near their outer ends for receiving a flange on a carrying body to mount the guard on the carrying body.

8. A guard of the character described comprising a body consisting of spaced ribs having notches in their inner edges, one of the notches being enlarged in two directions at its base to form a double, under-cut slot, a spiralled wire having one end seated in one portion of the under-cut portion of one of the notches and its first convolution seated in the other portion of said slot, successive convolutions of the wire being seated in other notches of the respective ribs.

In testimony whereof we affix our signatures.

FREDERICK D. PITTS.
ARTHUR OSTERLOO.
